UNITED STATES PATENT OFFICE.

GEORGE H. SANDERS, OF SAN JOSE, CALIFORNIA.

MAUSOLEUM.

Application filed March 23, 1925. Serial No. 17,633.

The present invention relates generally to mausoleums and more particularly to a combined ventilating and disinfecting apparatus for the crypts thereof.

5 Among the objects of this invention, are to provide means whereby each crypt may be provided with a suitable outlet for gases, such outlet being through a disinfectant liquid seal and a mercury seal; to provide 10 means whereby a plurality of crypts may be vented through a common ventilating system incorporated in the mausoleum; to provide a mausoleum which is simple in construction, efficient and reliable in the preservation 15 of the bodies, durable, and well adapted to the purpose for which it is designed; and in general, to provide such an improved ventilating and disinfecting system as will appear more fully from the following specification.

In the drawing

Figure 1 is a vertical section through a portion of the mausoleum embodying the features of my invention,

25 Fig. 2 is an enlarged detail section through one of the crypts thereof,

Fig. 3 is a still further enlarged detail section through the rear wall of one crypt, and

30 Fig. 4 is a similar view taken at right angles to that shown in Fig. 3.

Referring to the drawings in detail, it will be seen that the mausoleum which I have illustrated includes among other elements a 35 floor 5, a rear wall 6, and a roof 7. A ventilator 8 is provided in the roof 7 and a passage 9 is disposed under the roof 7 to communicate with the ventilator 8.

The roof passage 9 communicates with a 40 passage 10 formed between the rear wall 6 of the mausoleum and the rear wall 11 of a plurality of crypts 12. A floor passage 13 is provided under the floor 5 and under the bottom crypts 12 and communicates with the 45 bottom of the passage 10 so that a circulation of air will be had as indicated by the arrows in Fig. 1.

On the interior of the wall 11 there are 50 provided a plurality of depressions or recesses 14, one in each crypt 12. In each of these recesses 14, there is disposed a hermetical and disinfecting sealing device indicated generally by the letter A. The structure 55 of these devices are identical and only one will be described in detail, and attention is called particularly to Figs. 3 and 4.

A tank 15 is positioned in the bottom of the recess 14 and is constructed of some suitable durable material such as metal and is provided with a depending tube 16 leading 60 from the top thereof and terminating a distance from the bottom thereof. This tank is about two-thirds filled with a disinfectant liquid. A lead pipe 17 leads upwardly from the tank 15 at the top thereof and is provided intermediate its ends with a trap vent 65 18 filled with mercury. The upper end of this lead pipe 17 extends through the wall 11 so as to terminate in the passage 10.

It should be understood that a mausoleum 70 is constructed with the expectation that it will last indefinitely, that the entire building is only as strong as its weakest part is self evident, and in the art as it is familiar to me, it contemplates the use of a net work 75 of pipes, joints, etc., something like a plumbing system in a modern house. Experience shows that any mechanical connection along the lines of pipes, joints, etc., is prone to rust, and requires repair within a short span 80 of years. A mausoleum construction is such that once the structure is completed, it is impossible to make any repairs in the sanitation system. Considering the purpose to be the preservation of bodies interred within 85 the building, any sanitation system which admits the decomposition of a body practically confesses the uselessness of the mausoleum itself.

In my structure no such decomposition can 90 ever take place and my sanitation system is not at all dependent upon a system of pipes, joints, etc. It is true, I use a pipe, but that pipe is a lead pipe without joints or mechanical connections. It is a well known 95 fact that of all materials that might be used in such a system, lead is by far the most durable and in practice is everlasting.

The mausoleum itself will probably crumble before the short pieces of lead pipe 100 used in this system would deteriorate in any degree. Each crypt or compartment in my mausoleum is equipped with the metal containers which are located in the rear of each crypt being positioned in the recesses 14. 105 The pipes 17 are of a one-piece lead structure. Any gas forming in the crypts will seek the weakest points which would be the tubes 16.

The gas, therefore, will pass through the 110 liquid disinfectant in the tanks and then through the lead outlet pipes. The gas pres-

sure will force the mercury up into the lead pipes. As the mercury ascends the pipes, it naturally flattens out, thus leaving an opening for the gas to pass out into the passage 10 where the circulation of air will allow the disinfected air to escape through the roof ventilator. Both the mercury and the disinfectant hermetically seals the crypts and prevent decomposition of the bodies.

10 It will be apparent that the present embodiment of the invention which I have described in considerable detail has been disclosed merely by way of example and attains all the features of advantage enumerated as 15 desirable, in the statement of the invention and the above description.

It will further be apparent that numerous changes in the details of construction, in the materials, in the sizes, and in the combination 20 and arrangement of parts may be resorted to without departing from the spirit or scope of the invention as hereinafter claimed, or sacrificing any of its advantages.

Having thus described my invention, what 25 I claim as new is:—

1. A disinfectant sealing device for the

crypts of mausoleums including a tank adapted to be partially filled with a disinfectant liquid, an inlet tube leading downwardly from the top of the tank and terminating 30 within the liquid therein, and a one piece lead pipe leading upwardly from the top of the tank and having a trap bend therein filled with mercury.

2. In a mausoleum, a wall having a ventilating passage therethrough, a crypt formed in the mausoleum and provided with a wall in common with said wall of the mausoleum, said wall of the crypt being provided with a recess interiorly thereof, a 40 tank positioned in the bottom of the recess and adapted to be partially filled with a disinfectant liquid, an inlet tube leading downwardly from the top of the tank and terminating within the liquid therein, and a one-piece lead pipe leading upwardly from the top of the tank and bent to provide a trap filled with mercury and terminating in 45 the passage of the wall of the mausoleum.

In testimony whereof I affix my signature.

GEORGE H. SANDERS.
